(57) **CLAIM**

The ornamental design for a balance blocks play kit, as shown and described.

DESCRIPTION

FIG. 1 is a top, front, right perspective view of a balance blocks play kit, comprising a collection of pieces, showing my new design. The first part is shown separately for complete disclosure;

FIG. 2 is a right view of the first part, the left view being a mirror image thereof;

FIG. 3 is a top view of the first part, the bottom view being a mirror image thereof;

FIG. 4 is a front view of the first part, the rear view being a mirror image thereof;

FIG. 5 is a top, front, right perspective view of the second part, shown separately for complete disclosure;

FIG. 6 is a right view of the second part, the left view being a mirror image thereof;

FIG. 7 is a top view of the second part;

FIG. 8 is a front view of the second part, the rear view being a mirror image thereof;

FIG. 9 is a bottom view of the second part;

FIG. 10 is a top, front, right perspective view of the third part, shown separately for complete disclosure;

FIG. 11 is a right view of the third part, the left view being a mirror image thereof;

FIG. 12 is a top view of the third part;

FIG. 13 is a front view of the third part, the rear view being a mirror image thereof;

FIG. 14 is a bottom view of the third part;

FIG. 15 is a top, front, right perspective view of the fourth part, shown separately for complete disclosure;

FIG. 16 is a right view of the fourth part, the left view being a mirror image thereof;

FIG. 17 is a top view of the fourth part;

FIG. 18 is a front view of the fourth part, the rear view being a mirror image thereof;

FIG. 19 is a bottom view of the fourth part;

FIG. 20 is a top, front, right perspective view of the fifth part, shown separately for complete disclosure;

FIG. 21 is a right view of the fifth part, the left view being a mirror image thereof;

FIG. 22 is a top view of the fifth part;

FIG. 23 is a front view of the fifth part, the rear view being a mirror image thereof;

FIG. 24 is a bottom view of the fifth part;

FIG. 25 is a top, front, right perspective view of the sixth part, shown separately for complete disclosure;

FIG. 26 is a right view of the sixth part, the left view being a mirror image thereof;

FIG. 27 is a top view of the sixth part;

FIG. 28 is a front view of the sixth part, the rear view being a mirror image thereof;

FIG. 29 is a bottom view of the sixth part;

(Continued)

FIG. 30 is a top, front, right perspective view of the seventh part, shown separately for complete disclosure;
FIG. 31 is a right view of the seventh part, the left view being a mirror image thereof;
FIG. 32 is a top view of the seventh part;
FIG. 33 is a front view of the seventh part, the rear view being a mirror image thereof;
FIG. 34 is bottom view of the seventh part.
FIG. 35 is a top, front, right perspective view of the eighth part, shown separately for complete disclosure;
FIG. 36 is a right view of the eighth part, the left view being a mirror image thereof;
FIG. 37 is a top view of the eighth part;
FIG. 38 is a front view of the eighth part, the rear view being a mirror image thereof;
FIG. 39 is bottom view of the eighth part.
FIG. 40 is a top, front, right perspective view of the ninth part, shown separately for complete disclosure;
FIG. 41 is a right view of the ninth part, the left view being a mirror image thereof;
FIG. 42 is a top view of the ninth part;
FIG. 43 is a front view of the ninth part, the rear view being a mirror image thereof;
FIG. 44 is bottom view of the ninth part.
FIG. 45 is a top, front, right perspective view of the tenth part, shown separately for complete disclosure;
FIG. 46 is a right view of the tenth part, the left view being a mirror image thereof;
FIG. 47 is a top view of the tenth part, the bottom view being a mirror image thereof;
FIG. 48 is a front view of the tenth part, the rear view being a mirror image thereof;
FIG. 49 is a top, front, right perspective view of the eleventh part, shown separately for complete disclosure;
FIG. 50 is a top view of the eleventh part, the bottom view being a mirror image thereof, the dash-dot line depicts the boundary of the balance blocks play kit and forms no part of the claimed design;
FIG. 51 is a front view of the tenth part, the left, right, and rear views being mirror images thereof;

FIG. 52 is a top, front, right perspective view of the twelfth part, shown separately for complete disclosure;
FIG. 53 is a front view of the twelfth part, the rear view being a mirror image thereof;
FIG. 54 is a top view of the twelfth part;
FIG. 55 is a right view of the twelfth part, the left view being a mirror image thereof;
FIG. 56 is a bottom view of the twelfth part;
FIG. 57 is a top, front, right perspective view of the thirteenth part, shown separately for complete disclosure;
FIG. 58 is a right view of the thirteenth part, the left view being a mirror image thereof;
FIG. 59 is a top view of the thirteenth part;
FIG. 60 is a front view of the thirteenth part, the rear view being a mirror image thereof;
FIG. 61 is a bottom view of the thirteenth part;
FIG. 62 is a top, front, right perspective view of the fourteenth part, shown separately for complete disclosure;
FIG. 63 is a right view of the fourteenth part, the left view being a mirror image thereof;
FIG. 64 is a top view of the fourteenth part,
FIG. 65 is a front view of the fourteenth part, the rear view being a mirror image thereof;
FIG. 66 is a bottom view of the fourteenth part; and,
FIG. 67 is an alternative view showing the claimed design in condition of use.

The evenly dashed broken line showing of a child depicts environmental structure and forms no part of the claimed design.
